UNITED STATES PATENT OFFICE.

WILLIAM STARLING BURGESS, OF MARBLEHEAD, MASSACHUSETTS, ASSIGNOR TO
CURTISS AEROPLANE AND MOTOR CORPORATION, A CORPORATION OF NEW YORK.

HYDROAERO-MACHINE.

1,294,389.

Specification of Letters Patent. Patented Feb. 18, 1919.

Application filed October 28, 1916. Serial No. 128,338.

To all whom it may concern:

Be it known that I, WILLIAM STARLING BURGESS, a citizen of the United States, residing at Marblehead, in the county of Essex, sex and State of Massachusetts, have invented certain new and useful Improvements in Hydroaero-Machines, of which the following is a specification.

My invention relates to hydroaircraft and 10 the objects and advantages of the invention will appear from the following description and drawings. The features of the invention and the combination of parts constituting the invention will be hereinafter described and shown in their preferred form 15 and particularly pointed out in the claims.

Seaplanes and hydroaeroplanes, as known in the art, are generally, if not always, characterized by the support of the body of the 20 craft, at rest or in traveling upon the surface of the water, by one or more pontoons. Unlike hydroaeroplanes flying boats depend for water support, not upon pontoons, but a boat-like body having the characteristics of 25 a hydroplane. In hydroaeroplanes it is customary to locate the power plant interiorly of the fuselage or nacelle and in flying boats exteriorly of the hull and preferably (although not infrequently it is located in the 30 hull of the boat) intermediate the supporting or sustaining planes. These features of construction primarily distinguish the two types of machine.

Bearing in mind such distinguishing features, the present invention may be designated a hybrid machine, that is, a machine having the characteristics of both a hydroaeroplane and a flying boat. The nacelle or fuselage of the hydroaeroplane is eliminated 40 and the pontoon (there being but one) retained. In this latter respect the machine is likened to the hydroaeroplane. Forwardly of and upon the pontoon a decked cabin structure is erected to inclose the landing or 45 chassis struts, control mechanism and flying crew, but not the power plant. In this respect the machine is similar to the flying boat.

In a machine thus characterized the 50 resistant surfaces are appreciably reduced; the speed increased without a corresponding increase in propulsive force; the chassis struts inclosed and removed from view; production cost minimized; and ingress and egress

respectively to and from the cabin space 55 made possible without necessitating a climb either up and into the fuselage or nacelle or into the cockpit of the hull.

In describing my invention in detail, reference will be had to the accompanying 60 drawings wherein like characters of reference designate like or corresponding parts throughout the several views, of which:

Figure 1 is a side elevation of the machine; 65

Fig. 2 is a front end elevation, a portion of the wing surfaces having been removed, and

Fig. 3 is a top plan view.

In its preferred embodiment the machine 70 may be generally described as comprising swept back supporting surfaces 10 and 11 having a varying angle of incidence throughout (of the "Dunne" type), a main flotation body or central pontoon 12, end or wing pontoons 13, and a housing or false decking 14 constructed to inclose and remove from view the pontoon mounting. 75

Interwing stabilizing planes 15, vertical, trailing, wing-tip rudders 16 and ailerons 17 80 additionally characterize the machine. Directional control is obtained through manipulation of the rudder 16 and elevational control through manipulation of the ailerons 17. The wing formation insures inherent stability. 85

From the extreme forward end the bottom of the central pontoon 12 is extended on a gradual curve rearwardly and downwardly as indicated at 18 and thence rearwardly more horizontally as indicated at 19 for abrupt rearward termination at a planing step 20 formed in the pontoon bottom at a point in the vicinity of a transverse line projected vertically through the 90 center of gravity designated CG. From the step rearwardly the pontoon bottom extends slightly upwardly or at a salient angle to the forward hydroplaning bottom 18-19. 95

Chassis struts 21, inclined forwardly, interconnect the lower supporting surface 11 and the pontoon 12. The usual fuselage or nacelle, characteristic of hydroaeroplanes, is eliminated and the decked cabin structure 14 provided instead. This cabin structure 14 100 is erected forwardly of and upon the pontoon 12 to inclose the chassis struts 21, the control mechanism (not shown) and the 105

aviator or flying crew. To cut down the head resistance the false decking is given a streamline form.

Upon reference to Fig. 1 it will be noted 5 that the false decking 14 extends rearwardly beneath the lower supporting plane 11 to a point in the transverse vertical plane of the planing step 20, and that ample cabin space is thus provided for occupancy by the flying 10 crew. If used as a pleasure craft (and the machine is primarily designed with this in view) sleeping quarters and other accommodations may be provided interiorly of the decked cabin structure or housing 14.

15 Inwardly converging standards 22 are erected upon the pontoon 12 immediately aft of the cabin structure 14 for the support of the power unit 23 without the cabin and in a horizontal plane intermediate the supporting planes 10 and 11. It is intended to locate the center of thrust in the approximate horizontal plane of the center of resistance by the arrangement just disclosed.

The wing pontoons 13 constitute with the 25 main or central pontoon 12 a substantially triangular support for the machine while hydroplaning. Both of these pontoons are constructed to provide a hydroplaning bottom 24 which at its forward end extends upwardly and forwardly for termination forwardly beyond the forward end of the pontoon itself. Hangers 25 cross wired as at 26 support the end pontoons as desired.

It will be noted upon reference to Fig. 1, 30 assuming that the machine is at rest upon the surface of the water, that the line of thrust is so inclined with respect to the horizontal that a tendency is created to rise, in hydroplaning, by the forward end. The desired behavior immediately preceding aerial flight is in this way quickened. Tie wires 27, symmetrically arranged at opposite sides of the longitudinal axis of the machine, brace the opposed wings constituting the 35 lower supporting plane and take up drift strains incident to flight. Preferably these wires interconnect the respective wings and the central pontoon, the wires in one instance, engaging at one end the forward wing spar (not shown) of each wing at the 40 foot of one of the wing posts 28' which interconnect the wings and the pontoon 12 at the foot of one of the forward diagonal chassis struts 21, and in the other instance, the rear wing spar of each wing at the 45 foot of one of said posts and the pontoon at the foot of the mentioned chassis struts 21. Continuing wires or cables 28 tie the respective wings aft and at the foot of the standards 22.

60 The machine, as intimated, being particularly adaptable as a sportsman's or pleasure craft, provision should be made for ingress and egress respectively to and from the cabin without necessitating a climbing up 65 and into the fuselage or nacelle or into the

cockpit of the hull as heretofore. This unnecessary and objectionable feature is avoided by the formation of a door (not shown) at the aft end of the decking 14.

While in the foregoing there has been 70 illustrated in the drawings and described in the specification such combination and arrangement of elements as constitute the preferred construction or embodiment of this invention, it is nevertheless desired to emphasize the fact that interpretation of the invention should only be conclusive when made in the light of the subjoined claims. 75

What is claimed is:

1. In an aircraft, a main flotation body, 80 supporting surfaces, struts directly interconnecting said surfaces and said body, and a decked cabin structure built up around the struts to collectively inclose them, the height of the cabin structure being equal to the gap 85 between the body and the lower supporting surface.

2. In an aircraft, a main flotation body, supporting surfaces, and a decked cabin structure erected upon said body for occupancy by the flying crew, the height of the 90 cabin structure being equal to the gap between the body and the lower supporting surface.

3. In an aircraft, a main flotation body, 95 supporting surfaces, straight substantially vertically extending struts interconnecting said surfaces and said body, and a decked cabin structure erected upon said body to inclose said struts.

4. In an aircraft, a pontoon, supporting surfaces, struts interconnecting said pontoon and said surfaces, and a decked cabin structure erected forwardly of and upon said pontoon to inclose said struts and afford 105 cabin space for occupancy by the flying crew, that portion of the pontoon deck extended to the rear end of the decked cabin structure constituting a platform for use by the crew in entering and leaving the cabin 110 space.

5. In an aircraft, a main flotation body, supporting surfaces extended intermediately across the body in a transverse horizontal plane vertically removed from it, struts directly interconnecting said body and said surfaces, a propelling power plant, and supports for the propelling power plant erected upon said body aft of said surface-supporting struts. 115

6. In an aircraft, a main flotation body, supporting surfaces extended intermediately across the body in a transverse horizontal plane vertically removed from it, struts directly interconnecting said body and said surfaces, a power plant support erected on said body aft of said surface-supporting struts, and a propelling power plant mounted on said support nearer the rear end than the forward end of said body. 120 125 130

7. In an aircraft, a main flotation body, superposed supporting surfaces extended intermediately across said body in a transverse horizontal plane vertically above it, a 5 propelling power plant disposed in a horizontal plane intermediate the horizontal planes of said supporting surfaces and without said body, and supports for the propelling power plant erected on said body nearer 10 its rear end than its forward end.

8. In an aircraft, a pontoon, swept-back supporting surfaces, a power plant support erected upon the pontoon nearer its rear end than its forward end, a propelling power 15 plant mounted on said support within the angle formed by the swept back supporting surfaces, struts erected upon the pontoon forwardly of the power plant support for mounting the supporting surfaces and a 20 decked cabin structure inclosing the last mentioned struts.

9. In an aircraft, supporting surfaces, a pontoon, struts interconnecting said surfaces and said pontoon, a decked cabin structure 25 erected forwardly of and upon said pontoon to inclose said struts and afford cabin space

for occupancy by the flying crew, a power plant support erected upon said pontoon aft of said struts, and a propelling power plant mounted on said support for disposition entirely without said decked cabin structure. 30

10. In an aircraft, a pontoon, a wing structure extending intermediately across the pontoon in a horizontal plane vertically above it, chassis struts erected on the pontoon to support the wing structure, and a decked cabin structure inclosing the chassis struts, the deck of the pontoon affording a 35 floor for the cabin.

11. In an aircraft, a pontoon, a supporting surface, struts directly interconnecting the supporting surface and the pontoon and a decked cabin structure erected upon the pontoon to collectively inclose the struts, the cabin floor and cabin roof being formed by 40 the deck of the pontoon and the supporting surface respectively.

In testimony whereof I affix my signature.
WILLIAM STARLING BURGESS.
